UNITED STATES PATENT OFFICE.

CLIFFORD A. FLEMING, OF HUNTSVILLE, MISSOURI.

HAYSTACKER.

Application filed September 23, 1925. Serial No. 53,116.

This invention relates to hay stackers, one of its objects being to provide cooperating means whereby, during the operation of the stacker the head of the stacker will be moved upwardly relative to its supporting means and thence moved downwardly to its normal position, the entire operation being effected solely by pulling and thereafter releasing the operating cable.

10 A further object is to provide a stacker requiring less power to elevate the load a given distance than has been heretofore required, this being due to the fact that the distance of the stacker head from its fulcrum gradually increases as the head is moved upwardly.

15 Another object is to provide a hay stacker which is very compact in construction and which, when in normal position, occupies less space than other stackers capable of elevating to the same height.

20 A further object is to provide adjustable means for varying the height to which the head of the stacker will convey a load.

25 Another object is to provide simple and efficient means for reinforcing the working parts of the stacker so as to prevent them from swaying laterally while in operation.

30 Another object is to provide a hay stacker having a novel form of truck readily movable into and out of operative position and by the use of which the stacker can be moved easily from place to place.

35 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

40 In the accompanying drawings the preferred form of the invention has been shown.

In said drawings,

Figure 1 is a plan view of the hay stacker, showing the parts in their normal positions.

50 Figure 2 is a side elevation thereof.

Figure 3 is a side elevation showing the stacker head elevated to delivering position.

Figure 4 is an enlarged longitudinal section through a portion of the structure and showing the truck positioned to support one end of the apparatus for transportation.

Figure 5 is an end elevation of a portion of the machine.

Figure 6 is an enlarged section on line 6-6 Figure 5.

Referring to the figures by characters of reference 1 designates the main sills of the stacker, these being connected at one end by a cross beam 2, adjacent the other end by a cross beam 3 and, at an intermediate point 65 by a cross beam 4. Converging braces 5 connect the beams 2 and 4 so as to prevent lateral distortion of the frame formed by the sills and their connecting beams. Arms 6 are pivotally connected to the sills 1 close to the beam 3 and carry an axle 7 engaged by wheels 8. These arms with the connecting axle and the wheels form a truck and when it is not desired to use the truck for supporting one end of the mechanism the 70 arms 6 can be extended upwardly as shown in Figures 2 and 3. When it is desired to use the truck, however, said arms are swung downwardly so as to bring the wheels against the ground, these parts being held 75 so positioned by the weight of the stacker head resting on the arms 6 as hereinafter explained.

Extending upwardly from and secured to the side sills 1 adjacent those ends thereof 80 remote from the truck, are standards 9 connected, near their upper ends, by a cross beam 10. Another standard 11 is mounted on the middle portion of the cross beam 2 and is fastened to the middle portion of the 85 upper cross beam 10 and secured to the sides of the upper end portion of this standard 11 are parallel inclined beams 12 the lower ends of which are securely fastened to the middle portion of the cross beam 4 while the upper end portions thrust upon and extend upwardly beyond the beam 10 to which they are attached. Downwardly diverging 90 braces 13 are attached to the upper ends of these beams 12 and extend downwardly and are attached to the end portions of the beam 2. Thus the upstanding frame provided at one end of the machine is braced against 95 lateral sagging. A pulley 14 is journaled between the upper end portions of the inclined beams 12 and another pulley 15 is journaled between brackets 16 secured to said beams and to the upper end of the standard 11. See Figure 6. Inclined side 100 braces 17 connect the upper end portions of the standards 9 to the side sills 1.

Pivots connected to the upper ends of

the standards 9 are lifting beams 18 each of which is provided with a longitudinal slot 19. Reinforcing blocks 20 are attached to the upper end portions of standards 9 and 5 serve to strengthen the structure at these points where considerable strain is received. Pins 21 are removably mounted in the beams 18 adjacent the pivot ends thereof and are adapted to extend across the adjacent ends 10 of the slots 18. Each pin can be inserted into either of two spaced openings 22 in the beam.

Pivots connected to the ends of the cross beam 4 are lifting bars 23 the free end 15 portions of which are connected by cross strips 24 suitably braced as shown at 25. When the stacker is not in use one of these cross strips 24 can rest upon the arms 6 as shown in Figure 4 so as to force the wheels 20 8 downwardly below the ends of the sills 1. A pitman 26 is pivotally connected to each 25 of the lifting arms 23 close to its pivot 27 and each of these pitmen is pivotally connected, at its upper end, to one of the slotted beams 18, as shown at 28.

Converging lifting beams 29 are pivotally mounted upon a cross rod 30 or the like carried by the sills 1 and carry a pulley 31 between their upper ends. Braces 32 are attached to these converging beams adjacent the sides of the pulley 31 and are pivotally connected to the lifting arms 23 at 33.

Guide sleeves 34 are attached to the lifting arms 23 close to the free ends thereof and 35 are engaged by sliding arms 35 mounted on the lifting arms. These sliding arms also carry sleeves 36 which slidably engage and extend partly or entirely around the lifting arms 23. The sliding arms are provided, at 40 their outer or upper ends with cross beams 37 to which are connected the tines 38 and 39 of the stacker head 40. These tines 38 and 39 are disposed at obtuse angles in the preferred construction so that, during the operation of lifting a load the tines 39 will support the same whereas, during the completion of the lifting operation and during the delivery of the load said load will be supported by the tines 38. This construction 45 is a well known one and it is not deemed necessary to enter into a detailed description or to illustrate the same specifically. An elongated roller 40' in the form of a pipe or the like is mounted to travel within the slots 19 50 in beams 18 so that said beams thus constitute a track. The ends of this roller are in engagement with pitmen 41 pivotally connected to the sliding arms 35 by removable pins 42. These pins can be placed in any 55 one of a series of apertures 43 formed in each of the sliding arms 35.

One end of a hoisting cable 44 is attached 60 to a yoke 45 in which the pulley 31 is mounted to rotate. From this yoke the said cable 65 is extended over the pulley 15 and under the

same back to and under the pulley 31. It is then extended over said pulley 31 and back over the pulley 14. Thence the cable is extended downwardly under a pulley 45 connected to the cross beam 2 adjacent the 70 center thereof. The free end of the cable can be attached to any suitable means whereby the same can be drawn longitudinally for the purpose of operating the stacker. In order to prevent the stacker from 75 tilting under the strain resulting from this pull the extension arms 46 can be connected to and projected beyond the ends of the sills 1, these arms being reinforced by braces 47.

The upward swinging movement of the stacker head is cushioned by a compression spring 48 mounted between the center of the cross beams 3 and a cable 49 is attached to the center of one of the beams 37 of the 80 stacker head.

Under normal conditions the sliding arms 35 rest upon the lifting arms 23, so that the weight of the stacker head and the parts carried thereby is transferred to the arms 6 and the wheels 8 are caused to project below the sills 1 as shown in Figure 4 and as heretofore explained. With the parts thus located the beams 29 are inclined as shown in Figure 2 with the stacker head projecting outwardly beyond the ends of the sills. A team or a tractor can be hitched to the other end of the structure and said structure readily transported from place to place.

When the machine has been brought to 100 the place where the material is to be stacked, the lifting arms are swung upwardly so as to allow the arms 6 to be swung upwardly to the positions shown in Figures 2 and 3. Thus the sills 1 will rest firmly on the ground. At this time the roller or pipe 40' 105 is located in those portions of the slots 19 remote from the standards 9. The material to be stacked is placed upon the tines 39 and after the pins 42 have been placed in the 110 openings 43 nearest the stacker head the cable 44 is pulled to operate the stacker. The pulling of this cable causes the beams 29 to swing upwardly about their pivot 30 and, by reason of the connections 32 between 115 these beams and the lifting arms 23 said arms 23 will also swing upwardly about their pivots 27. As the sliding arms 35 are supported on the arms 23 they, too, will be 120 swung upwardly, carrying the stacker head with them. During this upward swinging of the parts the roller 40' will travel along the slots 19 and toward the pins 21. As long as the movement of the roller within the slots is not obstructed the sliding arms 35 will not change their positions relative to the lifting arms 23. By the time the roller 40' 125 comes against the pins 21 the weight of the load has been transferred from the tines 39 to the tines 38. Further pulling of the 130

cable 44 will cause the beams 29 to continue to swing towards the cross beam 10 but as the pitmen 41 cannot travel any further within the slots 19 they will exert a thrust 5 against the sliding arms 35 with the result that, during the further upward swinging movement of the stacker head, the arms 35 will be shifted longitudinally along the lifting arms 23 and the load carried by the 10 stacker head will be pushed almost straight upwardly to the predetermined level. When the stacker head is brought to the upper limit of its movement the tines 38 will be slightly inclined so that the load will 15 gravitate therefrom onto the stack. After the load has thus been elevated the cable 44 is paid out to permit the stacker head to return to its normal or lowermost position. During the first portion of this return movement 20 the sliding arms 35 will gravitate downwardly along the lifting arms 23 after which the pitmen 41 will draw the pipe or roller 40' along the slots 19 to its forward position therein. After the stack has been 25 built up to a certain height making it necessary to elevate the load to a higher level, the pins 42 are withdrawn from the apertures nearest the head 40 and the pitmen 41 are adjusted back so as to allow the pins 30 to be inserted into the next adjoining apertures 43. Thus during the next lifting operation of the stacker the head 40 will be raised to a still higher elevation. Thereafter pins 42 can be placed in the remaining 35 apertures 43 successively until the limit of elevation by the stacker has been reached. Obviously the closer the pins 42 are placed to the pivots of the lifting arms 23 the more extensive will be the sliding movement of 40 the arms 35 upon the lifting arms 23 and, consequently, the higher will be the lift of the load. Importance is attached to the fact that, by the use of the tracks formed by the slotted beams 18 together with the 45 pitmen 41 and the cooperating lifting arms and sliding arms 23 and 35 respectively the power required to elevate a load to a relatively high point is much less than has heretofore been necessary because the upward 50 movement of the load relative to the lifting arms begins after said arms have been elevated to points where the hoisting cable is relieved of much of the lifting strain.

What is claimed is:

55 1. In a stacker longitudinally slotted members mounted for swinging movement, lifting arms pivotally mounted, sliding arms upon the lifting arms, a stacker head carried by the sliding arms, pitmen pivotally mounted, sliding arms upon the lifting arms, a stacker head carried by the sliding arms, pitmen pivotally and adjustably connected to the sliding arms and slidably connected to the slotted members, pitman connections 60 between the lifting arms and the slotted

members, and means for swinging the lifting arms to upwardly extending positions, said pitmen and the slotted members cooperating to shift the sliding arms upwardly relative to the lifting arms during the completion of the swinging movement of the lifting arms. 70

2. In a stacker connected sills constituting a frame, longitudinally slotted members mounted to swing relative to the frame, lifting arms pivotally mounted on the frame, arms slidably mounted on the lifting arms, a stacker carried by said slidably mounted arms, pitmen connections between the sliding arms and the slotted members, said connections 75 being mounted for limited sliding movement relative to the slotted arms, pitmen connections between the lifting arms to the slotted members, and means for swinging the lifting arms relative to the frame. 80

3. In a stacker a frame including supporting sills, members mounted to swing relative to the frame, lifting arms pivotally connected to the frame, arms mounted to slide longitudinally of the lifting arms, a stacker head carried thereby, pitmen pivotally connected to the sliding arms and slidably engaging the pivoted members, pitmen connecting the lifting arms and the pivoted members and means for swinging the lifting arms relative to the frame, said pivoted members and the pitmen cooperating to shift the sliding arms upwardly during the completion of the upward swinging movement of the lifting arms. 90

4. In a stacker a frame including sills, arms pivotally connected to the sills, supporting wheels carried by the arms, lifting arms, mounted to swing relative to the sills, arms slidably mounted on the lifting arms, a stacker head carried by the sliding arms, means for swinging the lifting arms upwardly away from the sills, and means connecting the slidably mounted arms for engaging the wheel carrying arms when the stacker head 105 is lowered, thereby to force the wheels below the sills to support one end of the frame. 110

5. In a stacker connected sills, an upstanding frame thereon, slotted members pivotally connected to said frame, lifting arms pivotally connected to the sills, arms slidably mounted on the lifting arms, a stacker head carried by the slidably mounted arms, pitmen pivotally connected to the sliding arms and slidably engaging the slotted members, pitmen connecting the lifting arms and the slotted members, lifting beams pivotally connected to the sills, a connection between said beams and the lifting arms, and means for actuating said beams to swing the lifting arms upwardly and downwardly, said pitmen and members cooperating to shift the sliding arms upwardly relative to the lifting arms during the completion of the upward movement of the lifting arms. 120 125 130

6. In a stacker connected sills, a stacker head, an extensible connection between the sills and the stacker head for supporting said stacker head, means for swinging said connections upwardly to elevate the stacker head, a truck pivotally connected to the sills and including side arms and supporting wheels, said wheels being normally out of contact with the supporting surface, the said stacker head connection cooperating with the side arms of the truck when the stacker head is in its lowermost position, for thrusting the supporting wheels below the sills to support said sills at one end.
- 15 7. In a stacker connected sills, an up- standing frame adjacent one end thereof, a stacker head, an extensible connection between the stacker head and the sills, said connection including lifting arms and slid- 20 ing arms, members pivotally connected to the frame, pitman connections between the sliding arms and said members, said pitmen slidably engaging the members, pitmen connecting said members and the lifting arms, 25 said pitmen and members cooperating to shift the sliding arms upwardly and relative to the uplifting arms, thereby to elongate the connections between the stacker head and the sills during the completion of 30 the upward swinging movement of said connection, and means for swinging the said connection.
8. In a stacker connected sills, an up- standing frame adjacent one end thereof, 35 means extending from the sills and frame for holding the same against tilting, mem- bers pivotally connected to the frame, a stacker head, an extensible connection be- 40 tween the stacker head and sills mounted to swing relative to the sills, pitmen con- necting said members to the extensible con- 45 nection for lifting the members during the upward swinging of the stacker head con- nection, pitmen pivotally connected to the elongated stacker head connection and slid- 50 ably engaging the members during the first portion of the upward movement of the stacker head connection, said pitmen and members cooperating to elongate the stacker head connections during the completion of 55 the upward swinging movement thereof.
9. In a stacker the combination with con- 55 nected sills, of an upstanding frame, mem- bers pivotally connected thereto, a stacker head, an extensible connection between the 60 stacker head, and sills mounted to swing relative to the sills, pitmen connecting said members to the extensible connection for lifting the members during the upward 65 swinging of the stacker head connection, pitmen pivotally connected to the elongated stacker head connection and slidably engag- 70 ing the members during the first portion of the upward movement of the stacker head connection, said pitmen and members coop- erating to elongate the stacker head connec- 75 tions during the completion of the upward swinging movement thereof.
- In testimony that I claim the foregoing as my own, I have hereto affixed my signa- 70 ture.
- CLIFFORD A. FLEMING.
